SUCTION CLEANER

Donald G. Smellie, Canton, Ohio, assignor to The
Hoover Company, North Canton, Ohio, a cor-
poration of Ohio

Application May 28, 1930, Serial No. 456,389

19 Claims. (Cl. 15—13)

The present invention relates to suction cleaners and more particularly to new and novel agitating means for suction cleaners. The invention is characterized by the provision, in a suction cleaner, of an agitating member which performs the double function of agitating the surface covering undergoing cleaning and also of directing the dirt-removing air to the point of agitation.

10 The object of the present invention is the provision of a new and improved suction cleaner construction. Another object is the provision of a new and improved agitator for a suction cleaner. A still further object is the provision of a suction cleaner in which the point of surface agitation is coincident with the point of maximum air cleaning effectiveness. A further object is the provision of a suction cleaner in which the cleaning air enters the cleaner thru the agitator. Other and more specific objects will appear upon reading the following specification and considering the drawings attached thereto.

In the drawings in which like reference characters refer to like parts throughout:—

Fig. 1 is a side view, with certain parts broken away, of the preferred embodiment of the present invention.

Fig. 2 is a front view of the machine, shown in Fig. 1, with certain parts broken away.

Fig. 3, of the drawings, discloses a modified embodiment of the present invention.

Fig. 4 is a partial side view upon the line 4—4 of Fig. 3.

Fig. 5 is a view in perspective of the agitator used in Figs. 1 to 4 inclusive.

Fig. 6 discloses a modified embodiment of an agitator which may be used in the present invention.

Referring now to Figs. 1 and 2 in particular the reference character 1 indicates generally a cleaner constructed in accordance with the present invention and which comprises the usual parts of a suction cleaner including a motor casing 2 which houses a driving motor, not shown; a fan casing 3, forming a fan chamber 4 within which is positioned a suction fan 5 carried by the extended motor shaft 6; a nozzle 7 fixedly carried by the fan chamber 3 and opening therewith into the fan eye 8; front-supporting wheels 9, 9 and a rear-supporting wheel 10 provided with height-adjusting means, indicated generally by the reference character 11; and a handle bail 12 which is pivoted to the motor casing at 13 and by which the cleaner may be propelled over the surface covering. The aforescribed parts comprise the

usual parts of a suction cleaner and no invention here resides in their general arrangement.

Positioned within the mouth of the nozzle 7 is the agitator or tunnel indicated generally by the reference character 14 which comprises a hollow-cylindrical-body member 15 provided with spaced lips 16 and 17 which act as beating-agitating elements in the operation of the cleaner and which extend helically around the body member 15, as shown in Fig. 5, on its lower side and between 10 which an opening into the agitator 14 is provided. A supporting member 18 is provided at each end of the agitator which is provided with a bearing 19 adapted to rotatably receive a supporting pin 20 carried by the removable end 21 of 15 the nozzle 7. The end 21 of the nozzle is provided with an opening 22 connecting the ends of the air tunnel 14 with the atmosphere. Sealing means 23 in the form of suitable washers are provided between the ends of the agitator 14 and 20 the adjacent end plates 21 which prohibit the passage of air from the agitator or the exterior atmosphere into the nozzle at that point.

Rigidly attached to the body member 15 of agitator 14 is a rearwardly projecting member 24 25 provided with an indented portion or seat 24a for a purpose hereinafter described. Positioned within the tunnel 14 and secured to the end plates 21 is a shell or gate member 25 which is provided with a transversely extending slot 26. Sealing means 27 and 28 are carried by gate 25 and prevent leakage of air from the tunnel into the nozzle 7 between the adjacent walls of said gate and said tunnel.

The gate member 25 functions to close the 35 opening in the tunnel between lips 16 and 17 and prevent the passage of air therethrough except at the point of intersection of the opening and the slot where a diamond-shaped area will be presented through which air may be discharged. 40 Upon the alternate rotary rotation or oscillation of tunnel 14 the area mentioned travels back and forth the length of the lips 16 and 17.

Positioned within the nozzle 7 is an individual compartment 29 which is provided with a removable cover 30 in the forward face of the nozzle. Positioned within the housing 29 is the rotatable member 31 carried eccentrically upon the extended motor shaft 6. Member 31 is provided with a bearing surface 32 upon its exterior which is enclosed by a non-rotatable but 45 slidable member 33 which is fixedly attached at its projecting ends to a shaft 34 by means of the securing means 35. The lower end of shaft 34 is provided with a conical projection 36 which 50 55

- extends within the indented seat 24a in the member 24. The conical projection 36 has a smaller enclosed angle than the seat 25 permitting member 34 to be angularly tilted therein. 5 The end 36 of shaft 34 is maintained forcibly yet resiliently in contact with the seat 24a by means of spring 37 which is positioned between the under side of member 24 and the looped securing member 38 which is fixedly attached by 10 securing means 39 to member 34.

The extended end of motor shaft 6 is supported in the rear wall of housing 29 in nozzle 7 by means of the bearing indicated generally by the reference character 40. Sealing means, 15 indicated generally by the reference character 41, are positioned at the sides of bearing 40 on supporting shaft 6 and are held in place by front and rear housing plates 42 and 43 which are secured to the rear wall of the house 29 by 20 securing means 44. The sealing means function to protect the supporting bearing 40 from the dirt-laden air.

In the operation of the cleaner, rotation of the motor and the fan 5 creates a reduced pressure 25 within the fan chamber 4 and nozzle 7. Air is drawn through the mouth of the nozzle 7 and the surface covering is lifted until it contacts with the broad sealing lips 45 and 46 of said nozzle. The sealing lips serve to restrict 30 the quantity of air entering the nozzle thereunder to a minimum and after the seal has been made the greater part of air must enter the nozzle by means of the air tunnel 14, having first entered therein through inlets 22 at the 35 ends thereof. The rotation of the motor shaft 6 causes the eccentrically mounted member 31 to rotate resulting in the member 33 being displaced alternately upwardly and downwardly to a degree determined by the eccentricity of member 31 relative to the shaft 6. The member 33 being maintained in contact with the member 24 carries that member with it in its travel resulting in the alternate rotary movement or oscillation of agitator 14 in clockwise and counter-clockwise directions about the axis of the supporting pins 20. The displaced surface covering which is sealed between the lips 45 and 46 contacts the lips 16 and 17 of the agitator 14 which are, in effect, penetrating lips, that is, 50 have a width of the magnitude of the distance separating adjacent rows of pile or adjacent tufts of a single row of pile of a surface covering, and the movement of these lips upon said covering results in the flexing and bending of the pile with the resultant disturbance of the embedded foreign matter thereon. The curvature of the lips 16 and 17 upon the agitator 14 is such that the angular displacement of said agitator is just sufficient to cause said lips to 55 contact the surface covering along their entire length. As the pressure within the agitator 14 is atmospheric while that within the nozzle 7 outside the agitator 14 is reduced, air is drawn from said agitator through the area of coincidence of the slot 26 of the gate 25 and the opening between the lips 16 and 17 into the nozzle, and, as the point of surface contact of the helical lips 16 and 17 form two of the sides defining the area of discharge, it is seen that the construction 60 accomplishes the directing of the cleaning air to the point of positive agitation. This desired result is impossible in the usual suction cleaner in which the cleaning air enters under the nozzle lips while the agitation takes place 65 at some intermediate point. It is also clear 70 that some air is directed through the nozzle 7 into the nozzle 14.

from the construction that the area of discharge from the tunnel 14 into the nozzle 7 travels back and forth across the length of slot 26 as the tunnel is oscillated.

Referring now to Figs. 3 and 4 a modified embodiment of the present invention is disclosed in which the gate or shell member has been omitted thereby permitting air to escape along the entire length of the opening between the tunnel lips in the operation of the cleaner. The general arrangement is the same as that of the preferred embodiment, the agitator 14 being provided with a body member 15 which is supported at its ends by the supporting member 18 provided with bearing 19 which is adapted to receive the supporting pin 20 carried by the end plate 21 of the nozzle 7. The permanently attached rearwardly projecting member 24 is connected to and actuated by the reciprocated member 34, as aforescribed. Lips 16 and 17, which are also the beating-agitating elements, are provided upon the agitator 14 which extend helically thereon as shown in Fig. 5.

Referring now to Figs. 5 and 6 in particular agitating air tunnels capable of being used in the present invention are disclosed. Fig. 5 discloses a modification in which only one pair of lips are present which extend approximately the entire length of the agitator. The lips are of the narrow pile penetrating design. Fig. 6 discloses a modification in which a series of pairs of lips 48 and 49 are used. In each construction the angular displacement between the ends of the respective pairs of lips is substantially equal to the angular rotation to which the agitator is subjected.

In order that the present invention may be adapted for use with cleaning tools a removable nozzle section 50 adjacent the fan eye has been provided. Section 50 is held in place, in the operation of the machine as a suction cleaner, by the spring pressed detent 51. If it is desired to use cleaning tools with the machine it is only necessary to slightly withdraw the detent 51 from its seat 52 within the removable section 50 thereby permitting the displacement of said section. It is then possible to insert the convertor member of the dusting tools into the space formerly occupied by section 50 and secure in place by means of the detent 51.

From the foregoing it is clear that a new and novel suction cleaner has been provided in which the agitator is used as an air-directive means, while at the same time agitating the surface covering undergoing cleaning through being itself actuated with an alternate rotary movement.

I claim:—

1. In a suction cleaner, a nozzle, a movable agitating element in said nozzle adapted to contact a surface covering undergoing cleaning, a housing in said nozzle open to the atmosphere and containing a body of air at substantially atmospheric pressure and open to the nozzle adjacent the surface-contacting element, and means to impart an alternate rotary movement to said element.
2. In a suction cleaner, a nozzle, an agitator within said nozzle including a movable surface-contacting agitating element and means to direct air to the point of surface contact of said element, said agitator being hollow and being interiorly connected with a source of cleaning fluid exterior of said nozzle, and means to positively actuate said agitating element.

3. In a suction cleaner, a nozzle, an agitator in said nozzle including a movable surface-contacting elongated penetrating lip and means to direct air to the point of surface contact of said lip, said agitator being hollow and being interiorly connected to atmosphere, and means to positively actuate said lip.

4. In a suction cleaner, suction-creating means, a nozzle having a mouth connected to said means, broad sealing lips defining the sides of said mouth and restricting the flow of air into said nozzle, a hollow agitator in said nozzle open to the atmosphere and to the nozzle, the opening in said agitator being of such size that a relatively large part of the air drawn into said nozzle by said suction-creating means enters therethru, an agitating element upon said agitator extending substantially into the plane of the nozzle lips, and means to actuate said agitator with an alternate rotary motion, characterized by the fact that said agitator conveys the air entering the nozzle therethru substantially to the exact point of surface agitation by said agitating element.

5. In a suction cleaner, suction-creating means, a nozzle interiorly connected to said means and having a mouth, lips defining the sides of said mouth adapted to contact a surface covering lifted thereagainst by said suction-creating means, a hollow reciprocating agitator movably mounted in said nozzle and having a surface extended substantially into the plane of the nozzle lips, said agitator being interiorly connected to the atmosphere and having an outlet in its surface open to said nozzle, and means to positively actuate said agitator to move said outlet relative to a lifted surface covering between said lips.

6. In a suction cleaner a nozzle, broad sealing lips upon said nozzle adapted to contact the surface covering undergoing cleaning and functioning to minimize the flow of air therebetween into the nozzle, means to admit cleaning air into the suction nozzle comprising an agitating air tunnel within said nozzle interiorly connected with the atmosphere and containing air at substantially atmospheric pressure, said tunnel having a mouth extended substantially into the plane of the nozzle lips and agitating means upon said air tunnel adjacent said mouth, and means to provide said air tunnel with an alternate rotary movement.

7. In a suction cleaner a nozzle, lips upon said nozzle defining a mouth, means to create a reduced pressure in said nozzle, a spirally extending agitating element pivotally mounted in said nozzle, and adapted to contact the surface covering undergoing cleaning, means to actuate said element with an alternate rotary motion, means to exhaust cleaning air into said nozzle adjacent said element, and means to limit the escape of said air into said nozzle to the point of surface contact of said agitating element.

8. In a suction cleaner a nozzle, lips upon said nozzle defining a mouth, means to create a reduced pressure in said nozzle, an air tunnel in said nozzle interiorly connected with the atmosphere and having a spirally extending opening in its wall, a stationary slotted gate member positioned in said tunnel intersecting the opening therein and limiting the escape of air therefrom, and means to actuate said tunnel to move said opening relative to the slot in said gate to move the point of air discharge from said tunnel.

9. A suction cleaner comprising a nozzle, a

suction-creating device to draw air through said nozzle and an open-bottomed air tunnel open to the atmosphere and containing air at substantially atmospheric pressure positioned in said nozzle, said tunnel being provided with surface-contacting penetrating lips, and means to reciprocate said lips.

10. In a suction cleaner, a suction nozzle, lips upon said nozzle, means to draw air through said nozzle, a motor driving said means, an air tunnel interiorly connected to the atmosphere and provided with an opening to said nozzle in substantially the plane of the nozzle lips, surface-agitating means carried by said tunnel, and power-transmission means between said motor and said tunnel to reciprocate said tunnel.

11. In a device of the character described, a casing provided with an intake nozzle, a vibrating agitator provided with outlet nozzles to deliver air at a pressure greater than nozzle pressure within the intake nozzle during vibration of said agitator, means to supply air to the agitator and electrically actuated means to vibrate said agitator.

12. In a device of the character described, a casing having a chamber terminating in a nozzle, an agitator pivoted in said chamber and having its lower end positioned always within said nozzle, said agitator having an air passageway therethru and open to the surface covering undergoing cleaning, said agitator being connected to a source of air supply, and electrically actuated means to vibrate said agitator relative to said nozzle.

13. In a suction cleaner, a suction nozzle, spaced lips upon said nozzle defining the nozzle mouth, means to draw air thru said nozzle and to lift the surface covering undergoing cleaning against said nozzle lips, a movable air tunnel in said nozzle connected interiorly to a source of air pressure greater than that in said nozzle, and having an opening facing the surface covering undergoing cleaning, lips carried by said tunnel defining said opening and adapted to contact the surface covering undergoing cleaning, and means to reciprocate said air tunnel to cause the lips on said tunnel to agitate the said surface covering.

14. In a suction cleaner, a nozzle, an agitator in said nozzle including a movable surface-contacting agitating element and means to direct air to the point of surface contact of said element, said means being open to a source of pressure greater than that in said nozzle, and means to impart an alternate rotary movement to said element.

15. In a device of the character described, a casing having a chamber terminating in a nozzle, an agitator pivoted above its surface-contacting portion within said chamber and having its lower end positioned always within said nozzle, surface-contacting elements formed along the lower edge of said agitator and having air passageways therethrough constituting nozzles, means to supply air under pressure greater than that in the casing nozzle to said agitator, and electrically actuated means to vibrate said agitator.

16. In a device of the character described, a nozzle, agitating means in said nozzle including an agitating element and an air passageway connected to an air source and open to said nozzle adjacent the point of surface contact of said element, said agitator being mounted relative to said nozzle so that said agitating element is movable to deliver a beating blow to an object.

undergoing cleaning, and means to actuate said agitator to cause said element to deliver a beating blow.

17. In a suction cleaner, a nozzle, spaced lips upon said nozzle defining the nozzle mouth, means to draw air through said nozzle, an air tunnel in said nozzle connected interiorly to a source of air pressure greater than that in said nozzle, and having an opening facing the surface covering undergoing cleaning, lips carried by said tunnel for movement in a direction having a vertical component, said lips defining said opening and being adapted to contact the surface covering undergoing cleaning, and means to reciprocate said lips to agitate said surface covering.

18. In a suction cleaner, a nozzle, spaced lips upon said nozzle defining the nozzle mouth, means to draw air through said nozzle, an air tunnel in

said nozzle connected to air at pressure greater than the pressure in said nozzle, lips upon said tunnel defining an opening facing a surface covering undergoing cleaning, means mounting said tunnel so that said lips are movable in a path having a vertical component, said lips being adapted to contact an article undergoing cleaning to deliver a beating blow thereto, and means to reciprocate said lips.

19. In a device of the character described, a casing provided with an intake nozzle, a vibrating agitator provided with an outlet nozzle to deliver air under a pressure greater than the pressure in said intake nozzle within said intake nozzle during vibration of said agitator, means to supply air to said agitator and electrically actuated means to vibrate said agitator.

DONALD G. SMELLIE.
